COMBINED DISPLAY AND PACKAGING
CONTAINER FOR FOOD OR THE LIKE

Peter J. Le Cody, 5412 W. Ferdinand St.,
Chicago, Ill. 60644

Filed Apr. 1, 1971, Ser. No. 130,557

Term of patent 14 years

Int. Cl. D9—03

U.S. Cl. D9—220

FIG. 1

FIG. 2

FIG. 1 is a top plan view of a combined display and packaging container for food or the like showing my new design; and

FIG. 2 is an elevational view thereof.

I claim:

The ornamental design for a combined display and packaging container for food or the like, as shown.
